AUTOMATIC UNLOADER FOR ELEVATORS

Filed Oct. 14, 1927

UNITED STATES PATENT OFFICE

SAMUEL OLSON, OF CHICAGO, ILLINOIS, ASSIGNOR TO SAMUEL OLSON & COMPANY, OF CHICAGO, ILLINOIS, A CORPORATION OF ILLINOIS

AUTOMATIC UNLOADER FOR ELEVATORS

Application filed October 14, 1927. Serial No. 226,087.

This invention relates to automatic unloading elevators and more particularly to the type adapted to unload at several points. The object of this invention is to provide an improved construction, wherein a plurality of individual loads may be carried on one tray of the elevator and be individually discharged at different predetermined points along the path of travel of the elevator. It 10 consists in certain features and elements of construction in combination, as herein shown and described and as indicated in the claims.

In the drawings:

Figure 1 is a somewhat diagrammatic view 15 of an elevator embodying this invention, together with an outline of a continuous belt conveyor at its lower end for receiving loads from the down run side of the elevator.

Figure 2 is a horizontal transverse section 20 through the elevator looking down at the unloading mechanism, taken on line 2—2, Figure 1.

Figure 3 is a fragmentary side view taken 25 on line 3—3, Figure 1, inside the elevator casing showing the double strand of chain supporting the tray of compartments together with a load ejecting arm in registration with one of the compartments.

Figure 4 is a fragmentary detail section of 30 the ratchet detent mechanism for operating the load ejecting arms at intervals, corresponding to the spacing of the trays on the belts.

In the use of elevators for delivering loads 35 to various predetermined points along the path of travel it is frequently desirable to load onto one carrier several parcels to be delivered at different stations along the path of travel, during a single trip of the carrier; this 40 requires only one stop for the loading operation. In institutions, such as large hospitals, the charts or records of the patients are often kept in a main office, and calls for the charts of several of the patients by their attendants 45 on the various floors are frequently made at the same time. This is one class of service for which the present construction is well adapted.

In the drawing, Figure 1, illustrates some- 50 what diagrammatically an elevator compris-

ing a pair of endless chain belts, 1, trained over the usual head and foot wheels, 2 and 3, respectively. The casing for the elevator may be of any suitable construction. Cross bracing comprising angle irons, 4, is attached 55 to the walls of the casing for supporting the head and foot ends of the elevator proper, and it also serves to support the upwardly extending angle members, 5, spaced in pairs to form guide-way for the flanged rollers, 6, 60 of the chain belts, 1. Said rollers are mounted on the outer ends of cross rods, 7, extending through the pair of chain belts, 1, in substantially horizontal position. The cross rods and rollers may be spaced in the chains at 65 any desired intervals, but in this instance it is preferable that the spacing be the same as that of the trays. Each of the rods, 7, is adapted to partially support a tray, 8, having 70 a substantially horizontal base member, 9, extending outwardly from the chain belts. The outer edge of the base member is supported by braces, 10, extending obliquely and attached at their lower ends to the inner sides 75 of the chain belts. Each tray is provided with a plurality of load-carrying compartments, 11, extending transversely of the tray, formed by upstanding partitions, 12, which are fastened to the base member, 9. These partitions, may be of U-shape construction, 80 with their upper ends flanged outwardly for connection with the adjacent portions to form a rigid construction. Each compartment is intended to carry an individual load 85 to a predetermined station along the path of travel of the elevator.

At each floor level or other station point, at which loads are discharged, automatic unloading mechanism is provided, inside of the elevator for ejecting the load from the corresponding compartment of the tray, onto an inclined chute, 15, which discharges on to any suitable platform, herein shown as a table, 16. Each unloading mechanism comprises 90 a spider member, 17, having four radially extending arms, 18, at approximately right angles to each other, one of said arms normally extending downwardly in a vertical position and the adjacent forward arm extending laterally into the path of travel of the 100

elevator. Said spider is secured on a transversely extending shaft, 19, with which it pivots in suitable bearing brackets, 20, attached to the opposite inside angle guide members, 5, at a point above the chute, 15, so that the lower path of the swing of the arms is in approximate horizontal alignment with the top of said chute. It will be understood that the spiders of these various unloading mechanisms are mounted on their shafts in position, so that the arms, 18, extend in alignment for ejecting the contents from the particular compartment carrying a load to be discharged at that point.

15 The chain belts, 1, are provided with auxiliary cross rods, 21, at points above the trays, each of the said rods having guide rollers, 6, to run between the angle irons, 5. The rod, 21 is adapted to impinge against the under side of the forwardly extending arm of the spider as the elevator travels upwardly, thereby turning the spider so that the downwardly extending arm is swung forwardly through the compartment of the tray with which it is aligned for ejecting the load therefrom. When the spider has been thus rotated through a quarter turn, the active ejecting arm will have come to a substantially horizontal position. The bottom of the compartment then impinges against the underside of the said arm, to swing it in an upwardly direction out of the path of travel, and simultaneously swinging the adjacent lower arm up to a position to project laterally into the path of travel of the elevator, for encounter with the next cross rod, 21. An automatic detent device is provided for each unloading mechanism adjacent the end of shaft, 19, for aligning the spider arms so that one of said arms shall always stand thus in horizontal position in the path of travel. All the rollers, 6, on the cross rods, 7 and 21, on the same side as the detent mechanism are provided with relatively wide bearing flanges, 45 22, for actuating the detent to release the shaft, 19, and permit the spider to be revolved. Said detent comprises a ratchet member, 23, keyed to shaft, 19, near one end, having its outer periphery notched at 24, at 90° intervals. A combination member, 25, is pivotally connected to a depending lug 20^a of the bracket 20, secured to the angle guides 5, and has a trip finger, 26, extending into the path of the flange, 22, of the rollers, so as to be forced upwardly thereby, to disengage a pawl, 27, connected to member, 25, and formed for meshing in the notches, 24, of the ratchet, 23. The pawl is yieldingly held in engagement by a spring, 28, connected to the outer end of the member, 25, and to an angle guide, 5. It will thus be clear that the detent mechanism frees the spider to make a quarter turn each time a flange 22, of the roller, 6, engages the trip finger and that the arms of the spider 65 go through the discharging motion with the

aligned compartment of the tray, each time a tray passes the unloading mechanism whether the compartment is loaded or empty.

The undersides of the trays, which on the down run side of the elevator are the upper sides, may be advantageously used to carry loads down to the original starting or collecting point. A tray in passing around the foot wheels, as indicated in dotted lines at the bottom of the elevator, will permit an easy discharge of a load on to the curved deflector plate, 29, for delivery onto a continuous belt, 30, which may carry these loads to any desired point of discharge, herein shown as a table, 31.

It is mechanically necessary to provide a slight clearance in the pockets, 11, for the ejector arms, 18, and if a paper should stand in the pocket in this clearance space it might be missed by the ejector; therefore I prefer to make the bottoms of the pockets V-shaped or upwardly convex as shown at 12^a, so that the lower edge of a card or paper will slide toward one side wall thus insuring that the paper will lean against the opposite wall and will thus stand in the path of the ejector arm, 18.

I claim:

1. The combination of an elevator comprising endless belt means with a tray carried thereby, upstanding spaced partitions dividing the tray into a plurality of compartments; and unloading means for the several compartments at different points respectively along the path of travel, each of said means comprising an arm dimensioned and mounted to pass between a pair of adjacent partitions; a fixed pivotal mounting for said means disposed out of the path of travel of the elevator and means associated with said arm normally extending into said path and engageable with a part of the elevator for swinging the arm through one of the compartments to eject the contents thereof.

2. The combination of an elevator comprising a continuous belt with a tray carried horizontally thereby, spaced partitions dividing the tray into a plurality of compartments, unloading means for different compartments at different points along the path of travel, each of said means comprising a plurality of cooperating arms pivotally mounted on a transverse axis, one of said arms normally depending downwardly in alignment with one of the compartments and an adjacent arm extending laterally into the path of travel of the belt, means carried on the belt, engageable with the laterally extending arm whereby to swing the downwardly depending arm between the adjacent partitions of the compartment for ejecting the contents thereof.

3. The combination of an elevator comprising a continuous belt with a tray carried horizontally thereby, upright partitions spaced on the tray to form a transversely extending row of compartments, unloading means for

different compartments at different points along the path of travel, each of said means comprising a plurality of co-operating arms, extending in a vertical plane registering with one of said compartments, one of said arms projecting laterally into the path of travel of the belt, an adjacent lower arm normally depending downwardly in alignment with one of the compartments, and actuating means carried on the belt at a point upward of said tray to engage the laterally extending arm and swing it upwardly, whereby the downwardly depending arm is swung outward between the partitions of the corresponding compartment for ejecting the contents thereof, the further upward travel of the belt serving to swing the last mentioned arm upwardly to permit continued travel of said tray.

4. In the combination defined in claim 3, means associated with said unloading means for maintaining said arms in proper relation for engagement with the actuating means on the belt.

5. The combination of an elevator comprising an endless belt with a tray projecting therefrom, upright partitions dividing the tray into a plurality of compartments, unloading means for different compartments at different points along the path of travel, each of said means including a spider mounted for pivotal movement, said spider comprising radially extending arms at substantially right angles to each other, one of said arms normally depending downwardly in alignment with a particular compartment and an adjacent arm extending laterally into the path of travel of the belt, means on the belt upwardly of the tray for engaging said laterally extending arm and swinging it upwardly, whereby the adjacent downwardly depending arm is swung outward between the partitions of the said compartment for ejecting the contents thereof, the further upward travel of the belt serving to swing the ejecting arm upwardly to permit continued travel of the tray, together with detent means associated with said spider for raising said arms in position for such cooperation with said tray.

6. The combination of an elevator comprising endless belt means, a tray supported thereby, upstanding spaced partitions dividing said tray into a plurality of compartments, and automatic load ejecting means disposed at stations along the path of travel, each positioned to operate upon a load in a different compartment of the tray, whereby the placing of a load in a given compartment predetermines the station at which it will be discharged.

7. The combination of a carrier for papers, cards or other relatively thin objects, comprising a relatively narrow, vertically disposed and open ended pocket in which such objects may stand on edge, and an ejector member arranged to sweep through the pocket

for discharging its contents horizontally, the bottom wall of such pocket being upwardly convex, sloping downwardly toward the side walls for the purpose indicated.

8. The combination of an elevator which includes a tray subdivided into a plurality of load supporting spaces and automatic load ejecting means disposed at stations along the path of travel of the tray, each positioned to register with a different space of the same for ejecting a load from such space, whereby the placing of a load upon any given space of the tray predetermines the station at which it will be discharged.

9. In the combination defined in claim 8, said elevator including endless belt means and a plurality of similar trays, each subdivided into several load supporting spaces with a space of each tray positioned to register with the load ejecting means at each station.
